UNITED STATES PATENT OFFICE.

WILLIAM E. WINE, OF TOLEDO, OHIO.

CAR-DOOR LOCK.

Application filed May 5, 1921. Serial No. 467,003.

To all whom it may concern:

Be it known that I, WILLIAM E. WINE, a citizen of the United States, residing at Toledo, in the county of Lucas and State 5 of Ohio, have invented certain new and useful Improvements in Car-Door Locks, of which the following is a specification.

This invention relates to door-locking devices for railway cars or the like and has 10 for its principal object to provide improvements in the means or mechanism commonly provided for holding and releasing the drop doors of the cars, being particularly adapted for use with cars of the twin 15 hopper type. Another object is to provide means cooperating with a transversely arranged pair of doors, whereby both of such doors may be suitably supported and conveniently locked without the employment of 20 chains, toggles, or other winding mechanism. Other objects are to provide a mechanism of the type specified, conveniently located both with respect to the doors of the 25 car and the car structure itself, and within easy access of the workmen. With such general and other incidental objects in view the invention consists of the arrangement, formation and combination of parts as will be herein described and finally claimed.

30 In the accompanying drawings which show a preferred embodiment of the invention, Figure 1 is a fragmentary side elevational view of the lower corner of one of the hoppers of a coal car of the twin hopper type 35 with the mechanism of the present invention applied thereto. Figure 2 is a transverse sectional view through a portion of this hopper showing the present locking mechanism substantially in plan view, the 40 view being seen in the direction of the arrow 2, Figure 1. Figure 3 is an end elevational view of a portion of the hopper with the mechanism applied, this view being seen in the direction of the arrow 3, 45 Figure 1. Figure 4 is a diagrammatical view identifying the type of car and showing the location of the hopper depicted in fragment in the preceding figures. Figure 5 is a diagrammatical view showing, as in 50 cross section, the general arrangement of hoppers transversely of the car.

Referring to these drawings, the side of the hopper which may also be considered as an extension of the side of the car, is denoted by the numeral 1, the bottom of the 55 hopper being denoted by the numeral 2. The hopper, as shown, is that commonly employed on cars of the twin hopper type, having the hopper floor 2 inclined to form a chute for the discharge of the contents by 60 gravity. Such hoppers are ordinarily provided at each end of the car and there are customarily two such hoppers at each end, arranged side by side as indicated at 3 and 4 in Figure 5. The inner ends of these 65 hoppers are defined by hopper end sheets 5, with an intervening space which is occupied by the center sill construction 6 of the car.

Each of the hoppers is closed by means of a door 8, these doors being set upon an 70 inclined plane substantially at right angles to the plane of the bottom of the hopper or chute plate 2. The doors are hinged or pivoted along their upper edges at 9 to the car body, the free edges 10 being arranged to swing away from the open ends of the chute plates 2 when the doors are opened. No special mechanism is provided for the mechanical swinging of the doors 75 into closed positions as it has been found that if they are properly fitted they can be closed 80 by hand. It is among the objects of the invention to provide improved means for locking the doors after they are closed manually and to this end a bracket 11 is 85 secured to the side of the hopper by means of rivets 12. This bracket has a staple or other lock-engaging member 13 affixed to it and the door carries a pivoted locking member in the form of a hook 14 which is arranged to latch over the staple 13 when the doors are pulled shut, thus holding the doors 90 in closed position without the intervention of any unnecessary parts. When the hooks 14 are in holding position the hook lock or 95 dog 15 which is made in cam shape and pivoted to the bracket 11 by means of a rivet 16, is rotated about its pivot so as to contact the point 17 of the hook and prevent the accidental release of the same. 100 Formed integral with the cam 15 and on the opposite side of the pivot 16 is an extension

18 which is provided for forcing the eccentric cam into or out of hard engagement with the point 17 of the hook 14.

The extension 18 constitutes a shoulder, 5 which may be engaged by any suitable form of tool for forcibly rotating the cam either into or out of contact with the back of the hook 14.

It has been before explained that two 10 doors are arranged side by side as indicated in dotted lines in Figure 5. These are hinged independently to the car body but the hinges are in axial alignment so that the two doors may be swung in unison. This 15 is further provided for by means of a transverse beam 7 which extends across the outer faces of the two doors, substantially from side to side of the car or hoppers. The beam is made in the form of a structural channel 20 and the doors are both secured to this common beam which serves as a stiffener for them and hold them against bulging from the load. The support of the free edges of the doors against the hopper openings when 25 the doors are closed, is at the ends of the beam 7 only, hence it will be appreciated that this beam which spans practically the entire width of the car must be of considerable strength.

30 The door-locking hooks 14 are pivoted to the doors through the medium of a pivot casting or bracket 19 which is connected to the door plate by means of the rivets 20 and to the beam 7 by means of the rivets 21, this 35 casting tying the beam and the door plate together. The door plates extend substantially to the outer face of the hopper, and the beam 7 ends also substantially at the same place. The door-locking mechanism 40 lies in a plane, and is operable in that plane, just outside of the lines of the hopper, the hook portion of the mechanism being arranged to swing partly along the outer end of the door and partly along the outer face 45 of the hopper and into engagement with the staple 13 when the doors are in closed positions. The bracket 19, forming a connection between the beam 7 and the door plate, overreaches the edge of the door and extends 50 beyond the end of the beam so that its outer portion lies outside of the outer face of the hopper or car side. The hook 14 is pivoted to this bracket by means of the bolt 22, there being a pair of walls 23 and 55 24 formed upon the bracket in such manner as to provide a hook-accommodating space therebetween. The pivot bolt 22 passes transversely of the car through both of these walls, the hook thus swinging in a 60 plane substantially at right angle to the plane of the door. By the aforescribed arrangement considerable weight is saved and economy effected.

The doors for such cars are preferably 65 provided with out-turned marginal flanges

such as shown in the drawings. For this reason it is preferable that the stiffening beam such as 7 should not extend outwardly beyond the end of the door, but that it should be stopped off just inside of the line 70 of the marginal flange. The bracket 19 is then secured to the channel 7 and constitutes an extension or arm which extends over the out-turned flange. The door supporting mechanism is operable between this 75 arm and a relatively fixed portion of the car body.

While Figures 1, 2 and 3 show the details of the lock mechanism upon one end of the beam 7 only, it is to be understood that the 80 other end of the beam is similarly equipped, the outer face of the other hopper having a similar bracket and hook arrangement. This construction is denoted by the showing in dotted lines of the two brackets 19 in 85 Figure 5.

I have thus described a preferred embodiment of my invention. Other embodiments are contemplated, within the scope of the appended claims, without departing from the 90 spirit thereof.

What is claimed is:

1. A railway car having a door hinged upon the car body, a stiffening member affixed to the door and extending to near the 95 end of the same, a bracket near the end of the door connecting the stiffening member and the door, a door lock carried by the bracket, and a cooperating member carried by the car in a position for engagement thereby when the door is swung into closed position.

2. A railway car having a door hinged upon the car body, a stiffening member affixed to the door and extending to near the 105 edge of the door and to near the edge of the car body, a bracket affixed to the end of the stiffening member and extending slightly beyond the edge of the door and the car body and a door-locking mechanism operable 110 upon the said bracket beyond the edge of the door.

3. A railway car having a door, a lock for said door, a lock retaining member associated therewith, the same embodying a rotatable cam having an eccentric lock-retaining face to one side of its axis and means at the opposite side thereof for the manual rotation of the cam.

4. In a door device for railway cars, a 120 door-supporting latch, and means for holding the latch in supporting relationship with the door, the same embodying a rotatable eccentric cam arranged to contact a portion of the latch, the said cam being formed with a shoulder opposite its latch-contacting face and said shoulder being arranged for co-operation with a removable cam-rotating tool.

5. In a door device for railway cars, a 130

door hinged along one of its edges to the car body, the same having an out-turned marginal flange formed along one of its edges, a door-stiffening beam secured to the 5 outer face of the door, the same extending along the free edge of the door and terminating near the said marginal flange, and a door supporting arm secured to the end of the said stiffening beam, the same extending outward beyond the end of the door 10 and over the said marginal flange, and a door supporting mechanism operable between the said arm and a fixed portion of the car body.

In testimony whereof I affix my signature.
WILLIAM E. WINE.

DISCLAIMER

1,431,499.—*William E. Wine*, Toledo, Ohio. CAR-DOOR LOCK. Patent dated October 10, 1922. Disclaimer filed August 22, 1935, by the assignee, *Wine Railway Appliance Company*.

Hereby enters this disclaimer to that part of the thing patented which is claimed in said patent in the following words, to wit:

“1. A railway car having a door hinged upon the car body, a stiffening member affixed to the door and extending to near the end of the same, a bracket near the end of the door connecting the stiffening member and the door, a door lock carried by the bracket, and a cooperating member carried by the car in a position for engagement thereby when the door is swung into closed position.”
